UNITED STATES PATENT OFFICE

CHARLES A. DAHLEN, OF DULUTH, MINNESOTA

BUG MAKING MACHINE

Application filed December 4, 1929. Serial No. 411,628.

This invention relates to rug making machines, the principal object being to provide a more practical and economical machine for making rugs of practically unlimited length.

Another object is to provide such a machine especially adapted for the making rugs having different lengths of nap or pile.

Other advantages of the cooperation of the novel arrangement of parts of the device will appear in the following description thereof.

Referring now to the accompanying drawings, forming part of this application, and wherein like reference characters indicate like parts:

15 Figure 1 is a perspective view, looking at a machine embodying the invention from the head end thereof with a portion broken away;

Figure 2 is a perspective view of the machine from the tail end thereof;

Figure 3 is an enlarged diagrammatical cross-sectional view of the machine;

Figure 4 is an enlarged perspective view of the tail end of the machine as from the back 25 side thereof;

Figure 5 is a front elevation of the tail end of the machine;

Figure 6 is a perspective view of the loop cutter head.

20 The frame structure upon which the operating mechanism is mounted comprises the upright head end 1 and tail end 2, resting upon any suitable foundation and united at their lower opposite corners as by suitable

35 rods 3 and at the top thereof by the horizontal upright beam 4, central I-beam 5, and table beam 6, as well as other longitudinal reinforcing rods or bolts as desired.

From the head end of the machine there 40 extends a narrow platform 7 surmounted by a still narrower platform or track like member 8 which forms in combination a rack-like support for the reciprocable carriage. This support is sustained in any desired manner at 45 its outer end for example by the legs or horse 9.

The reciprocable carriage is of tubular construction and comprises the upper and lower arms 10 and 11 respectively, united as 50 by the upright member 12 forming a gener-

ally U-shaped carriage. The forward end of the upper member 10 terminates in the needle carrying head illustrated generally at 13 and the forward end of the lower member terminates in the cutter head illustrated generally at 14.

The preferred form of power mechanism is illustrated as employing an electric motor indicated at 15, mounted upon the head end 1 of the device, and which drives the countershaft 16 mounted thereabove, the latter in turn operating the needle head 13 as by the cable 17 passing through and about the triple sheaves 18, 19 and 20, and thence to and about the fixed sheave 21 on the beam 4 of the machine, thence back to and about the driving sheave 22 on the countershaft, thus providing power at all times to the needle head, irrespective of its position on the machine.

By suitable mechanism within the needle head 13, the small shaft 23 is given constant rotary motion which is imparted longitudinally of the carriage back to the opposite end thereof where it is connected by suitably encased beveled gears as at 24 to the inclined shaft 25, thence by similar beveled gears to the horizontal shaft 26 for operating the loop cutting mechanism, as clearly shown in Figure 6 of the drawings. It is obvious that the loop cutting mechanism must remain at all 20 times in fixed relation to the needle operating mechanism thereabove. The specific form of these two devices does not enter into my present invention.

To provide as nearly as possible non-frictional supports for the carriage, the upper arm 10 thereof is supported upon a series of rollers 27 which bear upon the beam 4 when over the machine and upon the member 8 of the extension rack when outwardly from the machine. The lower member 11 of the carriage is carried upon suitable laterally extended rollers 28 bearing upon the spaded elevated rods 29 above the member 7 of the support.

In the mechanism comprising the needle head there is included an intermittently driven gear wheel 30 which meshes at all times with the rack 31 which extends the full length of the beam; it being understood that the

uppermost central portion of the beam 4 is dovetailed as shown in Figure 2 for slidably holding the body portion of the needle head which is mounted thereupon and in the center of which upwardly extending dovetailed portion is formed the rack 31.

There is also carried in the needle head suitable mechanism for optionally operating the head manually either backwardly or forwardly, as well as means for stopping and starting the motion of the carriage without interfering with the continuous operation of the endless cable 17. The manual controlling device includes the counterbalanced crank arm 32, mounted upon the shaft 33 conveniently accessible to the operator of the device. By this arrangement when the needle carriage is thrown into action and operated by the power mechanism just described such operation is intermittent in step with the reciprocation of the needle and obviously may be controlled when desired by hand.

Detailed description of the loop cutting mechanism carried upon the inner terminous 25 of the lower member 11 of the carriage is not deemed essential, it being set forth in my co-pending application Serial Number 388,598, filed August 19th, 1929 and it will be obvious that any other form of loop cutting device 30 may be employed if desired.

Depending from the beam 4 is supported by the clips or brackets 34 the inclined rug engaging plate 35 the lower edge of which is spaced slightly above the adjacent edge of 35 the table 6 which is of fabricated structure including the slightly reduced and sharpened plate 36. This spaced relation between the sharpened edges of the plates 35 and 36 provides the channel through which the needle 40 reciprocates in the operation of the machine. The edges of these two plates are spaced vertically as well as horizontally, providing room for the back of the rug as it is fed through same during the process of making.

Attention is now directed to Figure 3 of the drawings for a description of the feeding of the back of the rug through the machine, and while I have shown the preferred arrangement of rollers and operating device for such a machine, it is evident that modifications in such arrangement may be resorted to without departing from the spirit of the invention. Back of the machine is mounted 55 in any desired manner the roller carrying shaft 37, the wooden roller commonly used for such purpose being shown at 38, and upon which is illustrated a full roll 39 of backing material or canvas as is usually employed, and 60 all of the rollers subsequently described are similarly mounted intermediate of the ends of the machine. The backing is then led from the supply roller 39 upwardly and over a small idler 40, downwardly and forwardly 65 about a similar idler 41, partially around

same and backwardly around the major prick point feeding roller 42 mounted upon a suitable shaft 43, thence upwardly and forwardly about a somewhat larger idler 44. From the roller 44 the rug back is led onto and over the table 6, across the needle gap or channel and under the plate 35 to and over the roller 45 which is similar in size to the roller 44, thence downwardly and about the second large prick point feeding roller 46 mounted upon the shaft 47 and about the small idler 48 above the prick point roller 46 to and about the final rug receiving roller 49 which may be positioned any place desired back of the machine; it being understood of course that after the back has left the needle channel it has become tufted and is a rug.

It will be noted that I have provided two power rollers mounted upon the shafts 43 and 47, and which two shafts extend outwardly 85 of the tail end member 2 and by which shafts the advancing of the rug back is accomplished in the following manner.

Upon the end of each shaft 43 and 47 is mounted a worm wheel, the one on the shaft 43 being indicated at 50 and the one on the shaft 47 at 51, while transverse to the end 2 of the machine is mounted a shaft 52 carrying a worm 53 meshing with the worm wheel 50, and a like worm 54 meshing with the worm 95 wheel 51, and these worms engage their respective wheels one on top and the other beneath, rotating said shafts in the opposed directions. As the rug back is fed into the machine from the supply roller 39 over the small rollers 40 and 41 and about the prick point roller 42 on the shaft 43, it may then be forcibly drawn by the rotation of the roller 42. This is accomplished by the hand rotation of the shaft 52, it having a spur gear 55 100 on the outer end thereof meshing with a spur gear not appearing on the drawings on the counter-shaft 56 which is operated by the crank 57.

As a novel feature in connection with the application of power to the shafts 43 and 47, it will be noted that the shaft 52 is made in two parts, one carrying the worm 54 and meshing with the worm wheel 51, and the other carrying the worm 53 meshing with the worm wheel 50, said shafts being telescopically united in any desired manner but each carrying a disc for cooperative engagement, said pair of discs being illustrated at 58 and one of which carries a spring controlled 115 keeper bolt 59 so that tension of the rug back intermediate of the prick point feeding rollers may be altered, that is to say, the operator may, if slack exists between these rollers, hold withdrawn the spring bolt 59 while the shaft 120 52 is being turned which will operate one of the rollers slightly in advance of the other. Then when the spring bolt is released and engages a new hole in the discs, the slack will 125 thus be taken up between the rollers.

There is illustrated a gear 60 upon the opposite end of the shaft 52 to that upon which the gear 55 is mounted, and which gear 60 meshes with a smaller gear 61 controlling any form of suitable counter or recording device so that record may be conveniently kept of the yardage.

The levers indicated at 62 and 63 are for the intermittent operation of the pile combing device which does not form part of my present invention.

The operation of the device is as follows:

Assuming that the rug backing has been fed through the machine as previously described ready for the weaving or rug making process, the needle head 13 is positioned at the head end of the machine as illustrated in Figure 2 of the drawings, when the yarn to be used is brought from any desired source and attached to the tension arm illustrated at 64, and from thence threaded as desired individually in the needle 37. Assuming also that the power belt 17 is supplying power to the needle head through the influence of the motor 15 being in action, the needle head is thrown into gear and commences immediate operation in tufting the rug; the carriage comprising the elements 10, 11 and 12 being advanced intermittently in step with the vertically reciprocable motion of the needle. At any point desired, as indicated by the pattern on the backing, the action of the needle carriage may be stopped by manual manipulation of the clutch lever 65, and any adjusting motion of the needle for changing the thread therein may be accomplished manually by the wheel 66 on the needle carriage. Or in the event of the carriage being at the opposite end of the machine and the line of tufting completed, the needle carriage is brought back to the head of the machine by manual operation of the crank 32. Usually however the rug back is advanced before the needle carriage is returned to the head of the machine, and this is accomplished as previously described by manual manipulation of the lever 57 which rotates the shaft 52 and the prick point wheels 42 and 46. Then when the needle is again properly threaded it is ready for another line of stitching transverse to the rug back. During the process of tufting thus described, it is obvious that the loop cutting mechanism illustrated at 14 and carried on the inner terminus of the member 11 of the carriage is in operation by virtue of the rotation of the shaft 26 and in step with the reciprocations of the needle; the loop cutting mechanism, however, as previously described, forming part of a separate invention.

Having thus described my invention, what I claim and desire to secure by Letters Patent, is:

1. A rug making machine of the character described comprising an upright elongated structure, spaced feeding rollers mounted

longitudinally therein, spaced tracks longitudinally of the upper portion of the structure, a carriage cooperating reciprocably with said tracks and carrying a needle head upon one track and a loop cutting head upon the other track.

2. A rug making machine of the character described comprising an upright elongated structure, spaced feeding rollers mounted longitudinally therein, spaced tracks longitudinally of the upper portion of the structure, a carriage cooperating reciprocably with said tracks and carrying a needle head upon one track and a loop cutting head upon the other track; said tracks extending beyond one end of the structure for the purpose described.

3. A rug making machine of the class described including rug feeding and guiding rollers, a table and rug guiding plate vertically and horizontally spaced for horizontal passage of the rug therebetween, a longitudinally movable needle operating head for forming the loops in the rug, and means intermediate of said rollers for varying the tension of the rug held therebetween.

4. A rug making machine of the character described comprising an upright structure, feeding rollers mounted longitudinally therein, tracks longitudinally of the upper portion of the structure, a carriage cooperating reciprocably with said tracks and carrying a needle head upon one track and a loop cutting head upon another track, and means intermediate of said rollers for varying the tension of the rug held therebetween.

5. A rug making machine of the character described comprising an upright structure, feeding rollers mounted longitudinally therein, tracks longitudinally of the upper portion of the structure, a carriage cooperating reciprocably with said tracks and carrying a needle head upon one track and a loop cutting head upon another track, and an adjustable rotative shaft for normally driving the rollers in opposite directions.

In testimony whereof I affix my signature.
CHARLES A. DAHLEN.
